UNITED STATES PATENT OFFICE.

ERNEST M. SKINNER, OF BOSTON, MASSACHUSETTS.

AUTOMATIC PIANO-PLAYER.

SPECIFICATION forming part of Letters Patent No. 663,368, dated December 4, 1900.

Application filed March 21, 1900. Serial No. 9,560. (No model.)

To all whom it may concern:

Be it known that I, ERNEST M. SKINNER, a citizen of the United States, residing at Boston, (Dorchester,) in the county of Suffolk and State of Massachusetts, have invented new and useful Improvements in Automatic Piano-Players, of which the following is a specification.

My invention resides in certain improvements in automatic piano-players, the object of the same being to provide means whereby greater facility in expression in devices of this kind may be obtained.

The invention consists in novel means for accenting particular notes, and I provide that in the group of notes struck at the same time any number of them may be actuated with greater force than the others, thereby giving to automatic piano-players a possibility and range in expression possessed heretofore only by the human hand. The individualizing of the notes is accomplished by suddenly increasing the air-tension in the air or vacuum chamber containing the primary pneumatics for an instant of time so short that in the most rapid music any one note may be selected and acted upon so quickly that the preceding and following notes will not be affected.

In carrying out my invention I employ a low-tension bellows for normally operating the keys, a high-tension bellows for operating the keys corresponding to the notes to be accented, and automatic means thrown into operation by the music-sheet for cutting in the high-tension bellows and cutting out the low-tension bellows.

The details of my invention will be fully set forth hereinafter and the novel features thereof will be defined in the claims.

In the drawings forming part of this specification, Figure 1 is a vertical section of my improved automatic piano-player. Fig. 2 is a plan view of the tracker or channel board. Fig. 3 is a view of a portion of the music-sheet. Fig. 4 is a detail sectional view showing a modified construction.

Like reference-numerals indicate like parts in the different views.

The air or vacuum chamber 1 contains the key-pneumatics 2 and communicates through the ports 3 with the large pneumatics 4, having the fingers 5 thereon for operating the

piano-keys 6. Each of the ports 3 is normally closed by a valve 7, whose stem 8 is connected with the key-pneumatic 2, as shown. 55 Each of the key-pneumatics 2 communicates through a passage 9 with an opening 10 in the upper surface of the tracker or channel board 11, over which passes the perforated music-sheet 12. The said music-sheet is wound on one of the rolls 13 and unwound from the other. It is provided with the usual note-perforations 14 14, corresponding to the music to be played, which perforations, as is usual in devices of this kind, are adapted to register with the proper openings 10 in the tracker-board 11. The air or vacuum chamber 1 also communicates through the wind-trunk 15 with the low-pressure air-reservoir or bellows 16 through a port 17, controlled by a check-valve 18, which opens inwardly or toward the low-pressure reservoir 16. The latter—that is, the low-pressure reservoir 16—communicates through the wind-trunk 19 with the high-pressure reservoir or bellows 20, the automatic valve 21 in the low-pressure reservoir 16 controlling the passage through the trunk 19. The main or high-tension bellows 20 is in communication through ports 22 with the feeding-bellows 23, the said ports 22 being controlled by an inwardly-opening check-valve 24 and the feeders 23 being open to the atmosphere through the ports 25, having valves 26, controlling the same. Said feeders are operated from the pedals 27 through the link or pitman 28, as shown. 75 80 85

Constructed as above described the apparatus will operate in the usual manner, all of the keys being actuated from the low-tension reservoir 16, and all of the notes will be struck with equal force. 90

My invention consists in forming in the tracker or channel board 10 a supplemental passage 29 and in the music-sheet 12 supplemental accent-perforations 30, adapted to register with the passage 29, and means controlled by these parts for cutting off the low-pressure reservoir 16 from the air or vacuum chamber 1 and cutting in the high-tension reservoir or bellows 20, so that the notes actuated thereby will be struck with greater force than those actuated from the low-pressure reservoir 16. In the event of a number of notes being struck simultaneously the 95 100

note - perforations 31 in the music-sheet 12, corresponding to the notes to be accented, are cut a short distance behind the other note-perforations and exactly opposite the accent-perforations 30. The higher air-tension operating the accented notes moves the piano-hammers so much more quickly than the notes which are not accented that it results in a simultaneous or practically simultaneous 5 attack upon the strings. In the first chord on the music-sheet 12 (shown in Fig. 3 of the drawings) the two slots 14 in advance of the two slots 31 register first with the openings 10 in the tracker-board 11. (Shown in Fig. 2.) The piano-hammers are then moved, say, one-half of the distance toward the piano-strings. The balance of the chord, consisting of the slots 31, then register in conjunction with the accent-hole 30 on the tracker-board. The 15 pressure in the key-pneumatic chamber 1 is instantly raised to double (by way of illustration) the tension obtaining when the first keys were acted upon. It will therefore be clear that these latter notes or, rather, the 20 hammers for striking the same will be acted upon with much greater rapidity, overtaking the others. It is true that the high tension is also acting upon the keys first struck; but they have progressed so far that the effect of 25 the high pressure is lost on them. The passage 29 at one end of the tracker or channel board 11 communicates with an accent-controlling pneumatic 32, which has connected to the movable part thereof the stem 33 of a 30 valve 34, normally closing the port 35 between the air or vacuum chamber 1 and the passage 36, leading to the pneumatic 37 for the accent-valve 38. The said accent-valve 38 normally closes the port 39, leading from the 35 main or high-tension bellows 20 to the wind-trunk 40, which communicates at its upper end with the air or vacuum chamber 1, and the stem 41 of said valve is connected to the movable part of the pneumatic 37.

40 Constructed as above described the operation of the device is as follows: When an accent-perforation 30 in the music-sheet 12 which lies opposite the note-perforation 31 on said sheet of the note to be accented registers with the passage 29 in the tracker or channel board 11, the pneumatic 32 is inflated by atmospheric air as against the low tension in the chamber 1 under the influence of the low-pressure reservoir 16. This causes the 45 depression of the valve 34 and the opening of communication between the air or vacuum chamber 1 and the pneumatic 37 through the port 35 and the passage 36. The influence of the air-tension from the low-pressure 50 reservoir 16 causes the deflation of the pneumatic 37, which serves to open the accent-valve 38 and open communication between the main or high-tension bellows 20 and the air or vacuum chamber 1 through the port 39 55 and the wind-trunk 40. The tension or pressure from the high-tension bellows 20 being

greater than that from the low-tension bellows 16 causes a quicker depression of the key-pneumatic 2, corresponding to the note on the music-sheet 12 opposite the accent-perforation 30, and also causes the key corresponding to said pneumatic 2 to be actuated with greater force, and thus accent the same. As soon as the high-tension bellows 20 is open to communication with the air or vacuum 60 chamber 1 the check-valve 18 is automatically closed in order that a sudden change in the air-tension in the chamber 1 may not be neutralized by the low-tension bellows 16. By my apparatus I can have an accompaniment of a fixed strength and produce a crescendo in the melody by collapsing the high-tension bellows 20, as by working the pedals 27 more rapidly. The spiral spring 42 in the bellows 20 exerts a greater force the more it 65 is compressed. If, therefore, the feeders 23 are worked slowly, they will collapse the bellows 20 but very little. If, however, they are worked rapidly, there is more air being taken from the bellows 20 than is being used through 70 the wind-trunk 19 and the accent-valve 38, and consequently with the valve 21 in the low-pressure bellows closed the bellows 20 will collapse in proportion to the degree of force exerted by the feeders 23. In this 75 respect the bellows 20 and feeders 23 are identical in their action with the ordinary cabinet-organ bellows. The accented notes are fed directly from the high-tension bellows and are cut in conjunction with the accent-hole and are perfectly independent of the 80 low-tension bellows 16 or the notes operated by it. Further, I can have a melody or theme of a fixed strength and increase the power of the accompaniment by collapsing the low-tension bellows 16 more fully—as, for instance, by opening an additional valve in 85 communication with the high-tension bellows 20, as illustrated in Fig. 4 of the drawings. An additional wind-trunk 43 is employed between the low-tension bellows 16 and the high-tension bellows 20, and in this wind-trunk is mounted a slide-valve 44. This is adapted to be operated by hand through the connections shown, consisting of the hand-lever 45, pitman 46, bell-crank lever 47, and link 48, the latter connected to the stem of the valve 44. After the valve 21 is closed the low-tension 90 bellows 16 may be still further compressed by the partial or complete opening of the slide-valve 44. The degree of its collapsing is governed by the supply and demand. The key-pneumatics are making a constant demand on the bellows 16, which demand is supplied normally through the valve 21. If the slide-valve 44 be opened, the collapsing of the bellows 16 is then not limited by the valve 21, but by said valve 44, as by opening the latter valve in excess of the demand made by the key-pneumatics and supplied by the governing-valve 21 the bellows 16 may be collapsed 95 to any desired degree. The result is an in-

creased air-tension in the bellows 16 and a consequent increase in the strength of the accompaniment.

It will be noted that my invention depends 5 for its successful operation upon the provision of two or more independent high and low tension bellows each of which may be varied without reference to the other and in the means for cutting out one when the other is 10 thrown into operation.

The check-valve 18, which controls the passage through the port 17, is an important feature of the apparatus, as the instant an increase in the tension takes place in the air or 15 vacuum chamber 1 said valve is closed and prevents the impulse from distributing the tension in the low-tension bellows 16 and also from wasting itself by simply collapsing the low-tension bellows. As the duration of the 20 impulse is but a fraction of a second, this is a matter of no small consideration.

Having thus described my invention, what I claim as new, and desire to secure by Letters Patent, is—

25 1. In an automatic piano-player, the combination with a low-tension bellows normally in communication with the air or vacuum chamber containing the primary or key pneumatics, of a high-tension bellows, and means 30 for throwing said high-tension bellows into communication with said chamber and simultaneously cutting off the low-tension bellows therefrom.

2. In an automatic piano-player, the combination with a low-tension bellows normally 35 in communication with the air or vacuum chamber containing the primary or key pneumatics, of a high-tension bellows, and automatic means for throwing said high-tension bellows into communication with said chamber and simultaneously cutting off the low-tension bellows therefrom.

3. In an automatic piano-player, the combination with a low-tension bellows, a wind- 45 trunk connecting said bellows with the air or vacuum chamber containing the primary or key pneumatics, and a normally-open check-valve controlling the passage through said wind-trunk, of a high-tension bellows, a wind 50 trunk or passage connecting said high-tension bellows with said chamber, a normally-closed accent-valve controlling the passage through the latter wind-trunk, and means for opening said accent-valve and simultaneously closing 55 said check-valve, as and for the purpose set forth.

4. In an automatic piano-player, the combination with a low-tension bellows, a wind- 60 trunk connecting said bellows with the air or vacuum chamber containing the primary or key pneumatics, and a normally-open check-valve controlling the passage through said wind-trunk, of a high-tension bellows, a wind 65 trunk or passage connecting said high-tension bellows with said chamber, a normally-closed accent-valve controlling the passage through

the latter wind-trunk, and automatic means for opening said accent-valve and simultaneously closing said check-valve, as and for the purpose set forth.

5. In an automatic piano-player, the combination with the air or vacuum chamber containing the primary or key pneumatics, a tracker or channel board having a series of passages therein communicating, respectively, with the several key or primary pneumatics, and having a supplemental passage therein, a low-tension bellows normally in communication with said air or vacuum chamber, and a normally-open check-valve controlling the passage between said low-tension bellows and said chamber, of a high-tension bellows, a wind trunk or passage connecting said high-tension bellows with said air or vacuum chamber, a normally-closed accent- 75 valve for controlling the passage through said wind-trunk, a pneumatic for operating said accent-valve, a passage connecting the accent-valve-operating pneumatic with said air or vacuum chamber, a valve normally closing 80 said passage, and a pneumatic for actuating said valve communicating with the supplemental passage in said tracker or channel board, whereby when said supplemental passage is uncovered by the registration there- 85 with of a slot in the music-sheet passing over said tracker-board, said accent-valve will be opened and communication between the low-tension bellows and said air or vacuum chamber 90 will be simultaneously closed.

6. In an automatic piano-player, the combination with a low-tension bellows normally in communication with the air or vacuum chamber containing the primary or key pneumatics, of a high-tension bellows, means for 105 throwing said high-tension bellows into communication with said chamber and simultaneously cutting off the low-tension bellows therefrom, and means for varying the tension of either of said bellows.

7. In an automatic piano-player, the combination with a low-tension bellows normally in communication with the air or vacuum chamber containing the primary or key pneumatics, of a high-tension bellows, means for 115 throwing said high-tension bellows into communication with said chamber and means for automatically throwing said low-tension bellows out of communication with said chamber when said high-tension bellows is thrown in, 120 and vice versa, whereby one, only, of said high and low tension bellows will be in communication with said vacuum-chamber at the same time.

In testimony whereof I have hereunto set 125 my hand in presence of two subscribing witnesses.

ERNEST M. SKINNER.
